UNITED STATES PATENT OFFICE.

ARTHUR GEO. BOOZER, JR., AND GEORGE HILL, OF TUCAPAU, SOUTH CAROLINA,
ASSIGNORS TO HOWARD D. COLMAN, LUTHER L. MILLER, AND HARRY A. SEVERSON,
COPARTNERS DOING BUSINESS AT ROCKFORD, ILLINOIS, AS BARBER-COLMAN COMPANY.

DOFFING-MACHINE FOR SPINNING-FRAMES.

1,142,012.

Specification of Letters Patent.

Patented June 8, 1915.

Application filed March 22, 1908. Serial No. 485,001.

To all whom it may concern:

Be it known that we, ARTHUR GEORGE BOOZER, Jr., and GEORGE HILL, both citizens of the United States, residing at Tucapau, 5 in the county of Spartanburg and State of South Carolina, have invented certain new and useful Improvements in Doffing-Machines for Spinning-Frames, of which the following is a specification.

10 This invention relates to certain new and useful improvements in doffing machines for spinning frames, the purpose being to provide a bobbin carrier or magazine from which the bobbins may be successively delivered to bobbin placing mechanism on the spinning frame to be placed thereby upon the empty spindles on the spinning frame, such carrier being mounted upon or carried by the spinning frame instead of being carried by the doffing mechanism.

15 One of the purposes of this invention is to relieve the traveling doffer of the weight of the magazine and bobbins necessary to supply the spindles on one side of the spinning frame, and in carrying our invention into use we prefer to provide the spinning frame with a structure or support that carries longitudinal magazines which are maintained so that the magazines may be raised

20 above the plane of the creel-board, so as not to interfere with the operatives in laying up roving on the creel-board.

25 In our prior applications we have shown different types of bobbin magazines or carriers mounted upon the doffer-frame and operatively connected thereto. Those magazines under certain circumstances do not meet all the requirements of automatic doffing mechanism, for instance a spinning frame having a hundred and twenty spindles on one side would require one size of magazine, whereas another spinning frame having a larger number would necessarily take a much higher magazine, therefore the 30 doffers for one spinning room would have to be supplied with magazines sufficient to supply bobbins to the longer spinning frame, and where the spinning frames are exceedingly long the magazines will have to be of 35 such a size as to be objectionable as a part

of a portable doffing machine. By relieving the doffer frame of the weight of the magazine and bobbins the work laid upon the motor is more constant, and the doffer is more readily handled, especially in moving 55 from one frame to another.

40 In the accompanying drawings Figure 1 is an end elevation showing one form of bobbin carrier and a doffer frame constructed for coöperation therewith. Fig. 2 is a front elevation of the doffer frame and magazine, parts of the spinning frame being shown in dotted lines, and Fig. 3 is a detail perspective view of a part of the bobbin carrier.

45 The spinning frame is of the usual type and has attached thereto rails 1 and 2, which provide horizontal ways, the upper rail having on its under side indentations with which the teeth of an intermittently driven spacing wheel engage to move the doffer 50 frame intermittently along the spinning frame. The doffer frame is provided with supporting wheels for engagement with the upper track or way, and with guide wheels that engage the under side of the lower rail, 55 such mechanism and the operative parts of the doffer mechanism being fully set forth in an application filed March 16th, 1909, Ser. No. 483,821.

60 The doffing means may be briefly described as comprising a bobbin-grasping device 3 mounted upon the upper end of a vertically reciprocatory bar 3^a, movement being imparted to said bar by a rotary gear or crank 3^b and intermediate connecting 65 links and arms indicated by reference numeral 3^c. The gear 3^b receives motion from a vertical shaft 3^d which is operatively connected at its lower end to a driving motor 3^e. The spacing wheel 4 which engages with 70 the rail 1 for advancing the doffer along the spinning frame, is fixed upon a shaft 4^a which is arranged to receive intermittent partial rotations from the shaft of gear 3^b. Also fixed on the shaft 4^a is a gear 5 with 75 which meshes a pinion 6, on a vertical shaft 7, the shaft 7 being thus intermittently driven. At its upper end the shaft 7 is provided with a spiral gear 8 that meshes with a gear 9 on the horizontally main- 80

tained shaft 10, the latter shaft having on its inner end a gear 11 that meshes with a gear 12 on a stub-shaft 13, which projects laterally from a bobbin receiver 14, and by use of the mechanism hereinbefore mentioned an intermittent revolving movement is imparted to the member 14.

The revoluble bobbin receiving member 14 is provided with a longitudinal opening, the ends thereof being enlarged to receive the enlarged base portions of the bobbins, and the actuating mechanism for this member is so organized that during the intermittent travel of the doffer mechanism a half turn is given to said revoluble member, and after said turn such member is locked in a vertical position for the reason that the shaft of the spacing wheel 4 is also locked to hold the doffer frame in positive engagement with the spinning frame.

Between the revoluble member 14 and the vertical standard of the doffer frame there is a segmental plate or guide 15 which will prevent a bobbin dropped into said revoluble member from falling out of the same during its movement upon its axis. This segmental plate may be attached to the upper end of the bobbin tube 16 or to the upper support therefor, and at its upper part the segmental plate carries a funnel 17 through which a bobbin passes when released from the magazine.

The bobbin releasing mechanism, is intermittently actuated and comprises an oscillatory plate 18, connected at its upper end by a link 19 to the depending member of a bell-crank 20, the forwardly extending arm of said bell-crank being connected to the lower end of a bar 21 which is attached at its upper end to a forwardly projecting arm of a bell-crank 22, mounted near the upper end of the standard, the latter bell-crank being connected to a retractor 23 by a link 24. The retractor 23 is maintained in sliding engagement with a horizontally maintained arm 25, which projects rearward or toward the spinning frame, such arm being provided with a follower or presser 26 shaped to engage a bobbin when in the magazine.

A supporting standard 27 is provided with suitable bearings or supports for the parts hereinbefore described. It will be noted that the retractor 23 is operatively connected to the means described in said application Serial No. 483,821 for holding a bobbin in the guide tube 16, the only change in the operative parts being to extend the end of the oscillatory member upward in order to give the proper range of movement to the bell-cranks mounted on the standard.

The bobbin magazine comprises a bobbin carrier which is horizontally maintained, preferably though not necessarily, in vertical alinement with the longitudinal axis of the spindles of the spinning frame. The

bobbin magazine or carrier 28 comprises a top-plate 29, an inner depending side 30, the lower end or edge being inturned to provide a bobbin engaging portion, and a front side having a depending portion of similar form which is cut away at intervals to provide openings 32. The openings 32 are filled by plates 33 having inturned lower ends, such plates being carried by resilient bars 34 attached to the front side-pieces 31 and provided with depending ends which lie in the path of the retractor 23. It will be seen that the magazine has at intervals retractile parts which when moved against the action of a spring will release a bobbin, the openings 32 and the retractile members of the magazine being spaced practically the same distance apart as the distance between the spindles. As the doffer frame stops so that the guide tube is in line with the spindles, a bobbin 35 will be released from the magazine.

The bobbin magazine or carrier is supported at its ends or at intervals by rods 35 which depend from cross-bars 36, said cross-bars being maintained by vertical bars 37 having at their ends rack-bars that are engaged by pinions on the shaft 38, the vertical bars 37 being suitably guided. When lowered the magazine is in operative relation with the doffing mechanism. When the bars are raised the magazine will be carried to a position where it will not interfere in any way with the operator reaching the creel-board. As shown by the drawings, the magazines extend the entire length of the spinning frame, and therefore the capacity of the magazines is equal to the number of spindles, and in practice the follower 26 will move the bobbins along the magazine.

A magazine of the construction shown can be readily filled from either end, and the bobbins are held with their large ends upward and depend from the magazine. This style of stationary magazine is attached directly to the spinning frame and may be filled by use of a detachable hopper constructed to carry sufficient bobbins to supply the magazine, the latter having a mark thereon to indicate when enough bobbins or quills have been inserted to supply all the spindles on one side of the spinning frame. It will be seen that the magazine constitutes a track or guide along which bobbins are movable longitudinally of the spinning frame into alinement with the respective spindles.

It is obvious that the particular form of construction of the magazine and its support may be varied so long as the same is kept within the terms and scope of the claims.

We claim:

1. In doffing mechanism for spinning frames, means secured to the spinning frame for carrying a plurality of bobbins, a bobbin placing mechanism which is movable

along the front of the spinning frame, and means carried by the bobbin placing mechanism for releasing bobbins from the carrier.

2. In bobbin placing mechanism for spinning frames, a spinning frame having secured thereto a longitudinal bobbin carrier which is adapted to carry a number of bobbins sufficient to supply the spindles on one side of the spinning frame, a bobbin placing mechanism which is movable along the spinning frame, and means upon the bobbin placing mechanism for moving the bobbins supported by said carrier along the carrier.

3. In doffing mechanism for spinning frames, the combination with a spinning frame having attached thereto a longitudinally maintained bobbin carrier, of a carriage which is movable along the spinning frame and mechanisms associated with said carriage for releasing an empty bobbin from the carrier and placing such empty bobbin upon a spindle of the spinning frame.

4. In doffing mechanism the combination with a spinning frame having maintained thereby a longitudinal bobbin carrier said carrier having retractile side located members for retaining bobbins in the carrier, of means on the doffing mechanism for actuating said retractile members to release a bobbin from the carrier.

5. In doffing mechanism for spinning frames, a horizontal bobbin carrier provided with retractile side members which constitute a part of the carrier, a follower on the doffing frame for moving bobbins along the carrier, and means for successive engagement with the side members to release a bobbin.

6. In doffing mechanism for spinning frames the combination with a longitudinally maintained bobbin carrier secured to the spinning frames and supported by the spinning frame, of a doffing mechanism which is movable along the front of the spinning frame, and means on the doffing mechanism co-operating with the bobbin carrier to take bobbins therefrom and place the same upon the spindles of the spinning frame.

7. In doffing mechanism for spinning frames, a carrier for a plurality of bobbins mounted upon the spinning frame and movable thereon vertically, means on the doffing frame for engagement with the carrier to release an individual bobbin therefrom, and means adapted to reverse the bobbin prior to placing the same upon a spindle of the spinning frame.

8. In combination with a spinning frame, a bobbin magazine maintained to be raised and lowered upon said spinning frame, a traveling doffing having a follower which is adapted to enter the bobbin magazine when the same is lowered, and laterally movable

means for actuating a part of the magazine to release a bobbin therefrom.

9. In combination with a spinning frame having thereon a longitudinally maintained bobbin carrier made up to carry in longitudinal alignment a sufficient number of bobbins to supply one side of the spinning frame, of a doffing mechanism which is movable along the front of the spinning frame said doffing mechanism having means thereon for successively taking bobbins from the carrier and for placing the same upon the spindles of the spinning frame.

10. In doffing mechanism, a longitudinal bobbin carrier, a follower for moving bobbins along the carrier, side located means for releasing a bobbin from the carrier, and means on the doffing mechanism for reversing the position of the bobbin before placing such bobbin upon a spindle.

11. In doffing mechanism for spinning frames, a doffing which embodies as a part thereof a revoluble bobbin receiver constructed to receive from a magazine a bobbin in reversed position for placing upon a spindle of a spinning frame, means for turning the bobbin receiver to reverse the bobbin, means constituting a part of the doffing mechanism for placing the bobbin upon a spindle of the spinning frame and a magazine carried by the spinning frame from which bobbins depend.

12. In combination with a spinning frame which is provided with a continuous bobbin carrier constructed to maintain in longitudinal alignment a plurality of bobbins sufficient to supply the spindles on one side of the spinning frame, of a doffing mechanism which is automatically and intermittently movable along the front of the spinning frame and means on the doffing mechanism for successively releasing a bobbin from the carrier and placing the same upon a spindle of the spinning frame.

13. In bobbin placing mechanism for spinning frames, a bobbin carrier maintained by the spinning frame above the horizontal plane of the spindles of the spinning frame, said bobbin carrier being adapted to receive and maintain bobbins in an inverted position, a bobbin placing mechanism which is movable along the front horizontally of the spinning frame, the same having means for releasing a bobbin from the carrier, means for reversing the bobbin and means for placing the reversed bobbin upon a spindle.

14. In bobbin placing mechanism for spinning frames, a longitudinally maintained bobbin carrier having side openings and retractile means in line with said openings, a depending portion attached to the retractile means for engagement with the larger portion of a bobbin so that the bobbin will be suspended from the carrier, a retractor on the bobbin placing mechanism,

- 1 a funnel, a segmental plate, a revoluble bobbin carrier below the funnel, and a guide tube in line with the revoluble bobbin carrier.
- 5 15. In bobbin placing mechanism for spinning frames, a horizontally maintained bobbin carrier constructed to receive the larger ends of bobbins so that the bobbins will depend from the carrier, retractile bobbin engaging means at intervals along the carrier, a bobbin placing mechanism having an arm that extends in the path of the depending bobbins, a retractor in sliding engagement with said arm, means connected to
- 10 15 and operated from a movable element of the bobbin placing mechanism for moving the retractor and an intermittently rotatable bobbin carrier for reversing a bobbin delivered thereto in order to place the bobbin in proper position for delivery to a spindle of the spinning frame.
- 15 16. In a doffer mechanism for spinning frames the combination with a bobbin carrier maintained by the spinning frame so as to be supported independent of the doffer mechanism the carrier having a longitudinal opening or slot through which the major portion of the bobbins pass, the side walls of the slot and means constituting a part
- 20 25 of the side walls engaging the bobbins to hold the same in engagement with the carrier, of a doffer mechanism which is movable along the front of the spinning frame, said doffer mechanism having thereon means for releasing bobbins one at a time from the carrier to supply the doffer mechanism with empty bobbins.
- 25 30 35 17. In a detachable and portable doffer mechanism for spinning frames, the combination with a spinning frame having tracks or ways for the doffer and a magazine for carrying bobbins in longitudinal alinement with the spindles of the spinning frame, of an automatically operated doffer that moves along the spinning frame, said doffer having a part that releases from the magazine a bobbin to automatically supply empty bobbins to the doffer as it moves along the spinning frame.
- 40 45 50 55 60 65 18. In combination with a spinning frame having vertically disposed supports, means engaging said supports for raising and lowering the same, transverse members attached to said supports and provided with means for connecting thereto longitudinal bobbin carriers; the carriers being of a type to maintain bobbins with their large ends within the carriers, bobbin placing mechanism movable along the spinning frame, and provided with followers that enter the bobbin carriers to engage and move a series of bobbins along the carriers, and means for releasing bobbins successively from the carriers and other means for changing end for end the bobbin released to deliver said
- 70 75 80 85 90 95 100 105 110 115 120 125 130 135 bobbin in proper position to a spindle of the spinning frame.
19. In combination with a spinning frame having means for attaching a bobbin removing and bobbin placing mechanism thereto, said frame also having a bobbin magazine which carries the bobbins in longitudinal alinement with the spindles on the frame and above the plane of such spindles, of a bobbin removing and placing mechanism which is movable along the front of the spinning frame and is provided with means thereon for releasing one at a time the bobbins from the magazine.
20. In doffing mechanism for spinning frames, the combination with a spinning frame, a bobbin magazine supported by the spinning frame so that the weight of the magazine and the bobbins carried thereby will be maintained independent of the bobbin placing and bobbin removing means, of bobbin placing and bobbin removing means mounted on a support that is movable along the spinning frame and means for successively releasing empty bobbins from the magazine to supply the bared spindles with bobbins.
21. In combination with a spinning frame, a bobbin placing mechanism which is movable along the spinning frame the same comprising a revoluble bobbin carrier, segmental means adjacent to the carrier for retaining a bobbin in said carrier as it is turned on its axis, a bobbin magazine on the spinning frame and means for releasing a bobbin from the magazine so that it will be deposited in the revoluble bobbin carrier.
22. In combination with a spinning frame having mounted thereon a bobbin magazine of sufficient capacity to maintain a number of bobbins equal to the number of spindles on the spinning frame, of a doffer mechanism for the spinning frame comprising an intermittently movable doffer having means thereon for releasing a bobbin from the magazine as the doffer makes its periodic movements along the front of the spinning frame.
23. In combination with a spinning frame having mounted thereon a longitudinal bobbin magazine from which a part of the bobbins depend, retractile means constituting a part of the bobbin retaining means of the magazine, of a doffer mechanism comprising an intermittently movable carriage having bobbin removing and bobbin placing means and means to effect from the magazine on the spinning frame an automatic feed of the bobbins one at a time to the doffer during its intermittent travel along the spinning frame.
24. In doffing mechanism for spinning frames, a carriage adapted to be associated with the spinning frame and to be movable along the same, a vertically reciprocatory

bobbin removing means to which movement is imparted when in vertical alinement with a spindle, a bobbin guide maintained by the carriage and movable therewith to be positioned over an empty spindle when the bobbin removing means is in vertical alinement with an adjacent spindle, a magazine for empty bobbins maintained so that the weight of the magazine and the bobbins carried thereby will be independent of the carriage having thereon the bobbin removing and bobbin placing means and means for releasing empty bobbins from the magazine for delivery to the bobbin guide of the bobbin placing mechanism.

25. In doffing mechanism for spinning frames, a carriage that is adapted to be associated with a spinning frame to travel along the frame, means maintained by the carriage for removing filled bobbins successively from the spindles of the spinning frame, means also maintained by the carriage for successively associating empty bobbins with the bared spindles, a magazine for empty bobbins associated with the spinning frame to be maintained independent of the carriage having the bobbin removing and bobbin placing means and means for releasing empty bobbins one at a time from the magazine.

30. In bobbin placing mechanism for spinning frames, a support, bobbin placing mechanism thereon, means for moving the support along the spinning frame, a magazine for empty bobbins mounted upon a support that is maintained independent of the support for the bobbin placing mechanism, and means coöoperating with the bobbin placing mechanism to release a bobbin from the magazine to said bobbin placing mechanism.

35. In combination with a spinning frame, a bobbin placing mechanism, means for associating the same with a spinning frame, means for effecting an intermittent travel of the bobbin placing mechanism along the spinning frame, and a bobbin magazine associated with the spinning frame to be maintained so that its weight will be carried otherwise than by the movable bobbin placing mechanism.

40. In doffing mechanism for spinning frames, a carriage having thereon bobbin removing and a bobbin-placing mechanism, means for moving the carriage to position the bobbin removing and the bobbin placing mechanism in vertical alinement with the spindles of the spinning frame, means for reciprocating the bobbin removing means when in alinement with a spindle having a bobbin thereon, a magazine for a plurality of empty bobbins sustained so that its weight will be maintained independent of the carriage having the bobbin removing and the bobbin placing mechanisms thereon and means associated with the bobbin plac-

ing mechanism for releasing bobbins from the magazine to said bobbin replacing mechanism.

45. In doffing mechanism for spinning frames, a magazine maintained by the spinning frame independent of the doffing mechanism, a revolute bobbin receiver maintained in rotary engagement with the doffing mechanism below the magazine, means on the doffing mechanism for releasing a bobbin from the magazine to be deposited in the revolute bobbin receiver, and means for rotating the bobbin receiver to place the bobbin carried thereby in position to be placed upon a bare spindle.

50. In doffing mechanism for spinning frames, a magazine for empty bobbins maintained by the spinning frame so that the weight of the magazine and the bobbins carried thereby will be supported independent of the doffing mechanism, a bobbin removing and a bobbin placing mechanism adapted to be associated with the spinning frame and comprising bobbin removing means and a guide tube mounted upon a carriage that is movable along the spinning frame to position the guide tube and the bobbin removing means on the carriage in vertical alinement with the spindles, means for vertically reciprocating the bobbin removing means when in alinement with a spindle to remove a filled bobbin from the spindle and means for releasing an empty bobbin from the magazine and placing the same upon a spindle which has previously been bared by the bobbin removing means.

55. The combination of a spinning frame provided along its side with operating mechanism, and an empty bobbin magazine above the operating mechanism and vertically movable out of the way of the operative.

60. The combination of a spinning frame and an elongated magazine for empty bobbins, said magazine extending longitudinally of and being supported by the spinning frame, the bobbins being shiftable longitudinally of the spinning frame.

65. The combination of a spinning frame and means for supporting a single row of empty bobbins for movement along the spinning frame.

70. The combination of a spinning frame and means extending longitudinally of said frame for supporting, in inverted position, a row of empty bobbins, the bobbins being slidable longitudinally of said supporting means.

75. The combination of a spinning frame having a row of spindles, an empty bobbin magazine, and means projecting outwardly from the middle portion of the spinning frame for supporting said magazine above and in the vertical plane of the row of spindles.

36. The combination of a spinning frame and a guide for empty bobbins, said guide extending longitudinally of the spinning frame and serving to slidably support the bobbins.

37. The combination of a spinning frame provided with a row of spaced spindles, means for supporting a single row of empty bobbins above the row of spindles, and 10 means for shifting the row of bobbins to bring individual bobbins into alignment with the respective spindles.

38. The combination of means for supporting a bobbin in inverted position, 15 means for placing a bobbin in upright position on a spindle of a spinning frame, means for releasing a bobbin from said supporting means, and means for turning the bobbin into upright position and transfer- 20 ring it to said placing means.

39. The combination of a spinning frame, a non-traveling empty-bobbin magazine mounted on said frame, and a bobbin-placing mechanism movable along the spinning 25 frame and receiving bobbins from said magazine.

40. In a doffer, means for supporting empty bobbins in non-upright position, a pivoted device for placing bobbins in up- 30 right position, said pivoted device receiving the bobbins from said supporting means, and donning means receiving bobbins from said pivoted device.

41. The combination of a spinning 35 frame, bobbin-placing mechanism mounted thereon to travel longitudinally of the frame, and an empty-bobbin magazine supported on said frame independently of said bobbin-placing mechanism and arranged to 40 supply empty bobbins to the latter.

42. The combination of a spinning frame, an empty-bobbin magazine mounted thereon and arranged to support bobbins in a single row extending above the spindles and longitudinally thereof, and bobbin-placing mechanism adapted to travel along the spinning frame and receive bobbins from said magazine and place them on the spindles.

43. In a bobbin-placing mechanism for 50 spinning frames, a magazine having a pair of parallel guideways spaced apart a distance less than the diameter of the butt of the bobbin, whereby a row of bobbins may be suspended by their butts on said guideways, said magazine further comprising a movable portion operable to permit the bobbins to descend out of the magazine.

44. In a bobbin-placing mechanism for 55 spinning machines, a magazine having a pair of parallel guideways adapted to receive a row of bobbins between them, the bobbins extending tips downwardly with the butts of the bobbins resting slidably on said guideways.

45. The combination with a spinning frame, of a doffing machine arranged to travel longitudinally along one side of said frame, and a bobbin magazine supported so that its weight will be independent of said 70 doffing machine and arranged to supply empty bobbins to the latter.

In testimony whereof we affix our signatures in presence of two witnesses.
